ATTORNEY.

UNITED STATES PATENT OFFICE.

ANTON M. KNUDSEN, OF OAK PARK, ILLINOIS, ASSIGNOR TO KELLOGG SWITCHBOARD AND SUPPLY COMPANY, OF CHICAGO, ILLINOIS, A CORPORATION OF ILLINOIS.

CONDENSER.

Application filed June 7, 1926. Serial No. 114,076.

My invention relates to condensers and has to do more particularly with that type in which the two plates of the condenser are formed of two continuous strips of tin-foil which lie respectively between strips of paper or any other suitable dielectric.

Condensers of the above type are provided with terminals which comprise thin metal ribbon strips which are slipped into position as the condenser is wound and to provide external terminals for the respective plates of the condenser, a connecting rack is used. This connecting rack supports a pair of suitable terminals to which the thin metal strip terminals are soldered and these terminals of the connecting rack provide means for connecting the plates of the condenser to an external circuit.

To eliminate the connecting rack to which the terminals of the condenser are soldered I provide a novel and improved terminal which is inserted as the condenser is wound and is of a one piece construction which provides for a direct connection between the plates of the condenser and the leads of an external circuit. The one piece terminal of my invention eliminates the soldered connection between strip terminals of the plates and the connecting rack and also eliminates the possibility of a loose connection as is often the case when a connecting rack is used.

Other objects and advantages will appear in the ensuing specification and for a more complete understanding of my invention reference may be had to the accompanying drawing in which like reference characters in the several views denote like parts and in which;

Fig. 1 is a perspective view illustrating the paper and tinfoil strips of a condenser assembled in a flat roll with the terminals of my invention in position relative to the tin foil strips or plates of the condenser.

Fig. 2 is a perspective view of a completed condenser illustrating the terminals of my invention in position, and

Fig. 3 is a perspective view of the terminal of my invention.

Referring now in detail to my invention as illustrated in the accompanying drawing and referring to Fig. 1 the two strips of tinfoil 2 and 3, each lie between two strips of paper 4, 5 and 6, 7 and are wound to form an oblong or oval shaped roll 9 and the completed con-

denser as illustrated in Fig. 2 is inserted in a suitable container the open end of which is filled with a suitable material such as sealing wax to exclude moisture. The terminals 10 and 11 are made of suitable conducting material such as thin sheet brass and are slipped into position and in engagement with the respective plates 2 and 3 of the condenser as the condenser roll 9 is being formed as illustrated in Fig. 1. As both terminals 10 and 11 are identical in construction a description of one will suffice. The body portion 12 of the terminal 10 which contacts with the plate of the condenser is of suitable width and length, its one end 13 being provided with an integrally formed tongue 14 extending at right angles to the body 12. This angular extending tongue 14 engages the ends of the rolled strips of paper of the completed condenser and prevents the terminal being forced down in the condenser after the condenser has been formed and pressed into a suitable shape as clearly illustrated in Fig. 2. The end 13 is provided with a reduced portion or terminal end 15 which is transversely bent or kinked as indicated at 16 to increase its rigidity and thus prevent it from bending.

From the above it is readily apparent that I provide a one piece terminal which is simple in construction, which insures a positive contact between the body 12 of the terminal, and its associated plate of the condenser and further that the terminal ends 15 which are integrally formed with the body of the terminal project above the wax filled container of the condenser to which conductors from an external circuit may be soldered. With this type of terminal I provide for a direct connection from the external conductors soldered to the terminal ends 15 and the plates of the condenser thus eliminating the soldered connections between the terminals of the plates and the terminals of the connecting rack, and also eliminating the possibility of a loose or poorly soldered connection which would necessarily reduce the efficiency of the condenser.

I have illustrated a particular size of terminal but it is to be understood that the terminals may be made of varying lengths and widths for the different size condensers.

Having described my invention what I desire to claim as new and secure by United States Letters Patent is:

1. A device of the character described in-

- cluding a condenser comprising layers of conducting and non-conducting material, an electric terminal comprising a flat body portion for contacting a layer of conducting material and adapted to be maintained in position by the layers of said condenser, a terminal end forming a continuation of the body portion and being small in size relative to said body portion, said terminal end being 5 transversely bent to increase its rigidity and means angularly disposed relative to the said body portion of said terminal for preventing movement of the said terminal by engaging said condenser.
- 10 2. A device of the character described including a condenser comprising layers of conducting and non-conducting materials, an electric terminal comprising a flat body portion for contacting a layer of conducting material and adapted to be maintained in position by said layers of material of said condenser, a terminal end forming a continuation of the body portion and being small in size relative to said body portion, and an angular tongue extension of said body portion 15
- 20 formed at right angles to said terminal end and said body portion and engaging the end of said condenser to prevent longitudinal movement of said terminal relative to said layer of conducting material. 30
3. A device of the character described including a condenser comprising layers of conducting and insulating materials, an electric terminal comprising a flat body portion for contacting a layer of conducting material 35 and adapted to be maintained in position by the layers of material of said condenser, a terminal end forming a continuation of the body portion being small in size relative to said body portion and transversely bent to increase its rigidity, and an angular tongue extension of said body portion extending at right angles to said terminal end and said body portion and engaging the end of said condenser to prevent longitudinal and lateral movement of said terminal relative to said plate. 40
- 45 In testimony whereof I have signed this specification.

ANTON M. KNUDSEN.
